UNITED STATES PATENT OFFICE.

WILLIAM S. HUYETTE, OF CHICAGO, ILLINOIS, ASSIGNOR TO WICKES BROS. OF CHICAGO, ILLINOIS, A CORPORATION OF MICHIGAN.

GAS-ENGINE VALVE.

No. 911,503.

Specification of Letters Patent.

Patented Feb. 2, 1909.

Application filed February 29, 1908. Serial No. 418,582.

To all whom it may concern:

Be it known that I, WILLIAM S. HUYETTE, a citizen of the United States, residing at Chicago, in the county of Cook and State of Illinois, have invented certain new and useful Improvements in Gas-Engine Valves; and I do hereby declare the following to be a full, clear, and exact description of the invention, such as will enable others skilled in the art to which it appertains to make and use the same.

My invention relates to valves for four-cycle gas engines.

One object is the provision of means for balancing the valve, thereby reducing the friction and the pressure of the valve in its seat.

Another object is the provision of means for cooling the valve.

20 A further object is to obviate the use of a valve stem and positively drive the valve directly from the crank shaft.

To these and other ends, my invention consists in certain novel features and combinations, such as will be more fully described hereinafter and particularly pointed out in the claims.

In the accompanying drawings, Figure 1 is a vertical cross-sectional view through the 30 cylinder head of an internal combustion engine, showing part of the cylinder and piston; Fig. 2 is a horizontal cross-sectional view through the head; Fig. 3 is a cross-sectional view taken longitudinally through the 35 valve shell on line x—x of Fig. 5; Fig. 4 is an end view showing the cap closing one end of the valve seat; Fig. 5 is a view of the closed larger end of the valve plug; and Fig. 6 is a fragmentary cross-sectional view of the 40 closed end of the valve shell in its seat.

While I have shown my valve structure as seated directly in the cylinder head, it can be connected in any suitable manner to the cylinder.

45 Referring to the drawings, (A) indicates a cylinder provided with a water jacket (1). A piston (2) is shown in the cylinder. The upper end of the cylinder is closed by a water-cooled head (3) having an engine port (4) adapted to admit the fresh charges to the cylinder and to permit the products of com-

bustion to be forced out of the cylinder. The engine port (4) leads from the upper end of the cylinder to a tapered valve-seat (5) formed in a valve casing in the head. 55

Located opposite each other and on either side of the engine port are the inlet port (6) and the exhaust port (7) separated from the engine port by the bridges (8). The width of the bridges may be increased 60 or diminished to obtain the requisite bearing for the valve plug, as well as to provide the proper area of the port openings. The valve seat extends transversely relative to the cylinder, the engine port entering the 65 valve seat intermediate its ends. A compression release cock (9) in communication with the cylinder is provided to relieve the compression in the cylinder and permit the engine to be turned over by hand when de- 70 sired.

As means for controlling the admission of fresh charges to and the exhaust of the spent gases from the cylinder, I have shown a stemless plug valve comprising a tapered 75 hollow valve shell (10) closed at its larger end, and being recessed or indented on one side intermediate its ends, as at (11) to form a valve-port. This shell is rotatably received in the valve seat, its smaller open end 80 projecting beyond the end of the valve seat. The projecting end of the valve is equipped with a pinion (12) driven in any convenient manner directly from the crank shaft and adapted to make one complete revolution 85 for every two revolutions of the crank shaft (not shown) of the engine.

Inlet and outlet tubes (13) and (14) respectively extend into the hollow interior of the valve shell through its open end and are 90 connected with a source of water supply (not shown) apart from the water-jacket of the cylinder. The water previously heated in the cylinder water-jacket is not led into the valve shell, but a supply of cool liquid 95 circulates in the shell and prevents overheating. The tubes pass through a packing plate (15) received in and closing the smaller end of the shell, the plate being suitably packed and remaining stationary as the 100 valve shell is rotated.

The explosion takes place in the cylinder

when the valve port (11) is in the position shown in Fig. 6. The force of the explosion acts upon the side of the tapered valve shell to force it endwise out of its seat. In other words, the explosion imparts an end thrust to the valve. If such end thrust is not overcome the fit of the valve in its seat would be destroyed and the valve would leak and work hard. At the same time the pressure counterbalancing the end thrust must not be too great or it will force the valve down in its seat and cause it to bind. As one means for counterbalancing the effect of the end-thrust exerted against the side of the valve shell by the explosion, I may provide the following construction:

A piston (18) projects from the closed end of the shell (10), such piston being of smaller area than the closed end of the shell. A cap (19) is screwed into the larger end of the valve casing or seat (5) and between the outer end of the piston and the inner face of the cap is located a socket (20), in which the piston is slidably received. The contacting faces of the socket and cap are machined and the cap is apertured, as at (21), to admit lubricant to such abutting surfaces. A semi-circumferential groove is formed exteriorly of the valve shell (16) near its closed larger end. A branch port (17) leads from the engine port (4) to a point in the valve seat (5) in alignment with the groove (16). The open face of the groove is at all times closed by the adjacent surface of the valve seat. A passage (22) leads from the groove (16) upward through the piston (18) discharging into the space between the end of the piston and the socket (20).

In a four-cycle engine, the piston on one of its in-strokes first compresses the previously admitted charge which is fired when the piston is at or nearly at its limit of inward movement. When the piston starts on its compression stroke, the pressure of the charge within the cylinder is gradually increased. When the charge is exploded, the pressure almost immediately reaches its maximum. The pressure gradually decreases as the piston proceeds on its power stroke. The groove (16) is of such length circumferentially of the rotating valve that it is brought into communication with the port (17) during the compression and power strokes of the engine and also during a part of the inlet or suction stroke, the object of which is to permit the pressure as it varies in the cylinder to equalize the pressure in the socket 20. Thus as the pressure gradually decreases in the cylinder as the piston is completing its power stroke, the pressure in the socket will also decrease and such of the pressure as still remains after the power stroke has been completed, will be exhausted from the socket

on the suction stroke of the piston. It is possible to run the groove 16 entirely around 65 the valve if desired in which event, the socket chamber would be in constant communication with the valve port 4. The intent of this portion of my invention is to counterbalance the valve during the compression and power 70 strokes of the engine in accordance with the varying pressures exerted by the charge within the cylinder against the tapered side of the valve shell. In other words, I produce a variable counterbalancing pressure against 75 the end of the valve to hold it in its seat, such counterbalancing pressure varying with the pressure exerted against the side of the valve shell. In this manner an excessive counterbalancing pressure which would cause the 80 valve to stick and bind is avoided. To illustrate this idea, I will describe the operation of my invention during the power stroke of the piston. When an explosion takes place in the cylinder, a portion of the expanding 85 gas is led via port (17), groove (16) and passage (22) to the socket (20), in which it expands and presses against the end of the piston to hold the valve shell in its seat against the end thrust imparted to the valve by the 90 expanding gases acting against the tapered side of the valve shell. As the pressure in the cylinder decreases, the pressure led to the socket (20) is similarly decreased, whereby the amount of counterbalancing pressure 95 possesses a fixed relation to the amount of pressure exerted against the side of the valve shell.

It will be observed that the counterbalancing pressure is not exerted against the entire 100 closed end of the valve, but only against the area of the piston and it is not strong enough to cause the valve to bind in its seat. No counterbalancing pressure is required during the suction and exhaust strokes. If the 105 pressure counterbalancing the end thrust were constant, as with a spring of sufficient rigidity to hold the valve seated at the time of explosion and the early part of the power stroke, the valve will be forced too hard into 110 its seat during the suction and exhaust strokes when no counterbalancing pressure is required. It is to be further noted that I provide a valve open at one end and closed at its opposite end. The pressure counterbalancing the end thrust of the valve is exerted against the closed end of the valve and the water is admitted and removed through the opposite open end. This construction is more simple than others. It prevents any 115 possibility of the water entering the bearing between the valve and its seat, and it admits of easy inspection and repair of the valve.

It is evident that changes might be made in the form and arrangement of the several 125 parts described without departing from the

spirit and scope of my invention and hence I do not wish to limit myself to the exact construction herein set forth.

Having thus fully disclosed my invention,

5. what I claim as new is—

1. The combination with an internal combustion engine provided with a valve casing having inlet and exhaust ports and an engine port, of a valve in the casing, means for closing one end of the valve casing, a piston carried by and of less area than the end of the valve, a socket in which the piston is slid- 10 ing received, the valve casing provided with a branch port leading from the engine port to the valve seat, the valve provided with a passage leading to the socket at one end, the opposite end of the passage adapted to register with the branch port during the compression and power strokes to create a 15 counterbalancing pressure against the end of the valve which varies with the pressure exerted against the side of the valve.

2. An internal combustion engine comprising a valve casing having a tapered valve seat and an engine port in communication with the seat, a tapered valve received in the seat, the valve being closed at one end, a cap closing one end of the seat, the casing provided with a branch port leading from the engine port to the valve seat, the valve provided with a semi-circumferential groove adapted to register with the branch port during the compression and power strokes, a piston on the closed end of the valve, and a socket in 35 which the piston is received, the valve provided with a passage leading from the groove through the piston and discharging into the socket.

3. An internal combustion engine comprising a valve casing having a valve seat and an engine port in communication with the seat, a valve in the seat, a piston on one end of the valve, a socket loosely received on the piston, a cap closing one end of the valve seat, the socket engaging the cap, the valve provided with a passage leading from the periphery of the valve and discharging into the socket through the piston, the casing having a branch port leading from the engine port, the end of the passage at the periphery of the valve adapted to register with the branch port during the compression and power strokes, and means for admitting lubricant to the abutting surfaces of the cap 55 and socket.

4. A valve for internal combustion engines comprising a tapering valve seat accessible from both ends, a rotatable hollow valve shell closed at one end and received in the seat, means for admitting and withdrawing water through one end only of the valve, and means for creating a pressure against the opposite closed end of the valve, the valve

being removable from its seat at that end opposite to and independently of the means 65 for admitting water to and withdrawing it from the valve.

5. The combination in an internal combustion engine, with a cylinder having a valve seat and a water jacket, of a hollow 70 rotary valve shell closed at one end and open at the opposite end, the valve received in the seat and controlling the admission and exhaust of the gas, and means inserted into the open end of the shell for admitting water to 75 and withdrawing it from the interior of the valve only, such means being independent of the water jacket, the valve being removable from its seat at that end opposite to and independently of the means for admitting 80 and withdrawing the water.

6. The combination in an internal combustion engine, of a hollow valve shell closed at one end and open at its opposite end, the shell controlling the admission of gas to and 85 its exhaust from the engine, inlet and outlet tubes directly inserted within the open end of the shell for conveying water to and removing it from the interior of the shell, 90 means for rotating the valve, and a stationary packing plate for closing the open end of the valve, the tubes passing through the plate.

7. An internal combustion engine comprising a valve casing closed at one end and 95 having inlet and exhaust ports and an engine port, a valve in the casing controlling the ports, the adjacent end of the valve being spaced apart from the closed end of the valve casing, the valve casing provided with 100 a branch port leading from the engine port to the valve seat, the valve provided with a passage leading to the space between the end of the valve and the closed end of the valve casing, the opposite end of the passage 105 adapted to register with the branch port during the compression and power strokes to create a counterbalancing pressure against the end of the valve variable with the variation in pressure exerted against the side of 110 the valve.

8. An internal combustion engine comprising a cylinder, a valve casing communicating with the cylinder and having inlet and exhaust ports, a rotary tapered valve 115 in the casing adapted to connect the cylinder with the inlet and exhaust ports successively, a piston on one end of the valve, a socket in which the piston is received whereby a chamber is formed between the piston and 120 the socket, the valve and valve casing provided with a communication between such chamber and the cylinder.

9. An internal combustion engine comprising a cylinder, a valve casing communicating with the cylinder and having 125

- inlet and exhaust ports, a rotary valve in
the casing adapted to connect the cylinder
with the inlet and exhaust ports successively,
a piston on one end of the valve, a socket
5 inclosing the piston whereby a chamber is
formed between the piston and socket, the
valve casing provided with a branch port
leading from the cylinder to the valve, the
latter provided with a circumferentially
10 extending groove adapted to register with
the branch port to create a counterbalancing
pressure against the end of the valve vari-
able with the variation in pressure exerted
against the side of the valve and to permit
the pressure in the chamber to exhaust. 15
In testimony whereof, I affix my signature
in presence of two witnesses.

WILLIAM S. HUYETTE.
